(No Model.)

C. E. MARSTON.
BOILER.

No. 445,473.

Patented Jan. 27, 1891.

UNITED STATES PATENT OFFICE.

CHARLES E. MARSTON, OF DOVER, NEW HAMPSHIRE.

BOILER.

SPECIFICATION forming part of Letters Patent No. 445,473, dated January 27, 1891.

Application filed March 1, 1890. Serial No. 342,240. (No model.)

To all whom it may concern:

Be it known that I, CHARLES E. MARSTON, of Dover, in the county of Strafford and State of New Hampshire, have invented a new and 5 Improved Boiler, of which the following is a full, clear, and exact description.

The object of the invention is to provide a new and improved boiler, which is simple and durable in construction, takes up very little 10 room, presents a great heating-surface, and permits of generating steam very rapidly.

The invention consists of a series of tubes each connected with the water-supply and steam-dome and provided with a branch pipe 15 extending from the said tube and opening into it near the top and bottom.

The invention also consists in certain parts and details and combinations of the same, as will be described hereinafter, and then pointed 20 out in the claims.

Reference is to be had to the accompanying drawings, forming a part of this specification, in which similar letters of reference indicate corresponding parts in all the figures.

25 Figure 1 is a sectional side elevation of the improvement on the line 1-1 of Fig. 2. Fig. 2 is a sectional plan view of the same on the line 2-2 of Fig. 1, and Fig. 3 is a side elevation of one of the tubes.

30 The improved boiler A is provided with a hollow ring-shaped base B, connected with the water-supply pipe C for filling the boiler with water. Inside of the ring-shaped base B may be arranged the fire-pot for heating the boiler 35 in the usual manner. From the top of the base B extends upward a series of pipes D, connected with vertically-arranged tubes E, set in a circle and having their outer sides curved, so that the several tubes form a wall 40 or shell for a combustion-chamber. One or two tubes E are left out to form an opening for a feed-door. The tubes may also be arranged in other forms than a circle. The inwardly-extending sides of each tube are inclined toward each other, as is plainly shown 45 in Fig. 2, so that the sides of the several tubes do not touch and the heat is permitted to readily pass onto the said sides.

From the upper end of each tube E extends 50 a tube F, opening into and supporting the steam-dome G, having a dished bottom G' and an inverted dished top G², from which leads

the steam-pipe H for carrying off the steam. The pipes F extend into the steam-dome G to about the horizontal plane, passing through 55 the joint of the bottom and top G' and G², respectively, so that water can collect in the dished bottom G' and remain there to protect said bottom G' from the heat of the fire-box.

Each of the tubes E is provided with a branch 60 pipe I, which extends from near the bottom of the tube inward and curves back again to enter the tube at or near its top above the water-line, as is plainly shown in Fig. 1. This branch pipe is preferably of wrought-iron, its 65 ends being cast into the side of the tube E, and it is also provided with series of outside annular flanges, as is plainly shown in Fig. 3. Annular flanges are also formed on the inner 70 sides of the tube E.

In the center of the bottom G' of the steam-dome G is secured a short pipe J, the upper 75 end of which is in line with the upper ends of the pipes F, while the lower end connects with the downwardly-extending pipe K, opening into a chamber L, from which extends downward a series of pipes N, opening into a second chamber O, connected by a pipe P with the feed-pipe C. The pipes N are also provided with annular flanges. 80

The operation is as follows: The water, passing 85 through the supply-pipe C, fills the base B, the pipes D, and extends into the tubes E and the branch pipes I to about the height shown in Fig. 1. The water also passes from 90 the feed-pipe C to the pipe P, to the chamber O, and extends in the pipes N to the same level as in the tubes E and the pipes I. Now when heat is generated in the base B the water in the several parts is rapidly heated and 95 steam is generated, which steam passes through the pipes F, K, and J to the steam-dome G and is taken from the latter by the pipe H to the apparatus or machine for utilizing its power. The water of condensation in 100 the steam-dome G accumulates in the dished bottom G', so that the latter is constantly covered with water, which protects the said bottom from the heat of the fire-box, and surplus water in the said steam-dome can pass readily through the pipes F into the tubes E, and through the center-pipe J, through the pipe K, and the chamber L to the pipes N. The heat passing up in the center of the boiler

heats the branch pipes I to a higher degree than the tubes E, so that the water in the said branch pipes I boils up through their upper ends and passes into the tops of the tubes E, 5 so that a complete circulation of the water takes place in each of the tubes by means of the branch pipe I. It will be seen that the water in boiling over the upper end of the branch pipes I into the upper ends of the 10 tubes E readily separates from the steam, which latter passes up to the dome G by the pipe F, while the water by its own weight falls down the tubes E until it strikes the water therein. It will further be seen that the 15 steam in passing up to the dome G is partly superheated in the pipes F, the compartment L, and the pipe K, so that the steam in the dome G is in a very dry state. It will further be seen that the branch pipes I project into 20 the interior space or combustion-chamber formed by the series of tubes E, and thus a large heating-surface is obtained, which, in connection with the large heating-surface of the pipes N, the chambers O and L, as well as 25 of the tubes E, permits of generating steam very quickly.

Having thus described my invention, what I claim as new, and desire to secure by Letters Patent, is—

- 30 1. In a steam-boiler, the combination, with a dome having a dish-shaped bottom and a hollow base, of a series of vertical tubes arranged to form a combustion-chamber, with three sides of each tube presented to the combustion-chamber, and tubes provided with inwardly-curving branch pipes, the top end of said pipes to discharge back into the vertical tubes above the water-line in said tubes, and short pipes connecting the tubes 35 40 with the dome, projecting into the dome and above the bottom thereof, substantially as shown and described.

2. In a boiler, the combination, with a dome having a dish-shaped bottom, of a chamber below the dome, a pipe connecting the chamber and dome, said pipe projecting into the dome above the bottom thereof, a second chamber below the first-named chamber and communicating with the water-supply, and vertical pipes connecting the two chambers, 45 substantially as described.

3. In a boiler, the combination of a dome having a dish-shaped bottom, a ring-shaped base, vertical tubes communicating with the base and dome and provided with inwardly-curved branch pipes, a chamber below the dome and communicating therewith, a second chamber communicating with the water-supply, and vertical tubes connecting the two chambers, substantially as herein shown 55 60 and described.

4. In a steam-boiler, the combination of a dome having a dish-shaped bottom, vertical tubes provided with curved branch pipes and arranged to form a combustion-chamber, a 65 series of pipes leading from the tubes into the dome, with their ends projecting above the bottom thereof, a chamber below the dome and provided with an upwardly-extending pipe, a short pipe secured to the center of the bottom of the steam-dome and in communication with the pipe of the said chamber, a second chamber below the first-named chamber, and pipes connecting the two chambers, the vertical tubes and the lower 70 75 chamber being connected with the water-supply, substantially as described.

CHARLES E. MARSTON.
